UNITED STATES PATENT OFFICE.

SAMUEL WHITE LINDSEY, OF MIDDLEBROOK, ARKANSAS.

CURRENT MOTOR.

Application filed May 27, 1920. Serial No. 384,663.

To all whom it may concern:

Be it known that I, SAMUEL W. LINDSEY, a citizen of the United States, residing at Middlebrook, in the county of Randolph and 5 State of Arkansas, have invented a new and useful Current Motor, of which the following is a specification.

This invention relates to hydraulic motors of that type which are operated by running 10 streams.

The objects of the invention are to provide a floating current motor having water wheels which are adjustable vertically and are provided with means by which all the 15 water wheels are turned by approximately an equal current force.

General objects are to provide a current motor which is efficient in its operation and easy to handle, and capable of a considerable 20 range of adjustability to meet varied water conditions.

The invention will be best understood from a consideration of the following detailed description taken in connection with 25 the accompanying drawings forming part of this specification, with the understanding, however, that the invention is not confined to any strict conformity with the showing in the drawings, but may be changed and 30 modified so long as such changes and modifications mark no material departure from the salient features of the invention as expressed in the appended claim.

In the drawings:—

35 Fig. 1 is a top plan view of the preferred embodiment of the invention.

Fig. 2 is a side elevation of the same.

Fig. 3 is a section on the line 3—3 of Fig. 1.

40 Figs. 4, 5 and 6 are detail views of one of the water wheels, Fig. 4 being a plan view, Fig. 5 a front elevation, and Fig. 6 a rear elevation.

The invention comprises a floating structure including two parallel substantially rectangular floats 10 connected by a deck 11, each having water-tight compartments 12 to provide sufficient buoyancy to support the heavy machinery of the apparatus.

50 A pair of longitudinally-extending vanes 13 are secured vertically to the under side of each of the floats 10, and bracing elements 14 hold each vane upon the respective float. The two vanes converge toward one end of 55 the structure, as indicated in dotted lines in Fig. 1, the distance between the vanes near

the forward end of the floats being approximately the width of the structure, while the distance between the vanes near the other end of the floats is but slightly greater than 60 the diameter of one of the water wheels.

The deck of the floating structure is broken away or left open, as indicated at 15 in Fig. 1, to provide a plurality of spaces or wells into or out of which the water 65 wheels and attendant parts may be moved. The wells 15 are bordered by side rails 16 rising above the deck 11 and by rails 17 at the ends. Beams 18 supported upon the rails 17 rise in converging relation. Between the upper ends of the pairs of beams 70 18 provided for each well, a shaft 19 is supported, which shaft carries several pulleys 20 secured thereto. A frame is slidably mounted in guides provided on upright 75 beams 18^a intermediate the converging beams 18. These frames each comprise horizontal members 22 joined at their ends with vertical sliding members 23. Near the upper end of each sliding frame a shaft 24 80 is mounted, which shaft lies below but parallel with the horizontal member 22. Each shaft 24 mounts a sprocket wheel 25. A countershaft 28 is supported in bearings 29 on the deck, and a sprocket wheel 30 secured 85 to the countershaft. Pinions 27 are secured to each end of the countershaft, and sprocket chains 26 meshing with the pinions 27 and with the sprocket wheels 25 on the shaft 24 enable the countershaft to be rotated by one 90 or more of the shafts 24.

Each shaft 24 also carries a pinion 31 at one end, which pinion is driven by an end chain 32 meshing with the pinion 34 on a lower shaft 35 carried at the lower ends of 95 the sliding members 23. The shafts 35 also carry a plurality of water wheels 36. Obviously, when the water wheels are turned by the current, the shafts 24 will be revolved, which will in turn drive the counter-shaft 28, from which power may be derived by means of the sprocket wheel 30.

The drawings in Figs. 1 and 2 show each shaft 35 as provided with three water wheels 36. It will be clear, however, that more or less than this number of water wheels may be employed, as desired, depending upon the water flow which is available, the swiftness of current, etc. The construction of the water wheels is illustrated in some detail in 110 Figs. 4, 5 and 6. Here the wheels are shown as comprising a plurality of blades 37 so

shaped as to yield a maximum power output. In Fig. 5, the vanes 37 are shown as having their inner ends bent angularly, as at 39, and fitted in to the hub 38 of the wheel. In Fig. 5, 6, the rear of the wheel is shown where the inner ends of the blades 40 are fitted into the hub 38 in slots which receive the blades without bending. While this is the preferred way of constructing the water wheels of the 10 present apparatus, the invention is not to be construed as limited to the precise water wheels described but is to be considered as independent of the particular water wheel employed.

15 It is desirable to raise or lower the shafts 35 with their water wheels so that under different conditions of flowage, or when power of the current is not needed, the water wheels may be raised partly or wholly out of the 20 water. In order to permit this, the frames are connected with cables 21 passing over pulleys 20 and running down to windlasses 41 (Fig. 1). Preferably there will be a pair of cables 21 for each frame and the windlasses 41 for each set of water wheels will be connected by a shaft 43. At each end of the shaft 43 cranks 42 will be provided.

The structure is designed to be towed to 30 the middle of a stream or to the swiftest running portion thereof and there anchored. Because of the buoyancy chambers it will float high above the water-line even though the water wheels be raised out of the stream. The flowing water enters between the wide 35 open ends of the vanes 13 and its force is concentrated by said vanes upon the successive wheels. The setting of the vanes is such that the power output of each water wheel is substantially the same even though there 40 may be six or more water wheels in horizontal alinement, as in the illustrated embodiment of the invention. At will the depth of one or more of the sets of water wheels may be varied. Thus, if desirable, one of the 45 water wheel sets may turn just below the

surface of the water, while the rear set may turn at a greater depth, with both sets driving the same shaft. Power from the sprocket wheel 30 may be utilized to drive machinery installed on the floating structure 50 itself or it may be utilized to drive machinery installed on the shore. Obviously, while sprocket wheels and chains have been described as forming a part of the apparatus, in many cases pulleys and belts, shafts and 55 gearing, or equivalent power translating means may be employed. While only two independent sets of water wheels have been disclosed, three or more may be employed, or in small installations but a single set may be 60 used.

What is claimed is:—

A current motor comprising a floating structure having a well open to the water, a plurality of frames movable vertically in the 65 well and independently of each other, a plurality of water wheels mounted on shafts carried by each movable frame, a shaft mounted at the top of each movable frame, gearing between each of said shafts and the 70 shafts carrying the water wheels, a countershaft supported on the deck of said structure, a flexible means operatively connecting the countershaft with each of said shafts mounted on the movable frames, said 75 countershaft forming a common means for transmitting motion from the independently movable shafts, rigid elevated frames mounted upon said structure and having guides for the movement of said movable frames, 80 a shaft at the top of said rigid frames, a windlass, and cables mounted on each windlass and passing over pulleys on the last-mentioned shaft and connected to each sliding frame for raising and lowering the latter within well defined limits.

In testimony, that I claim the foregoing as my own, I have hereto affixed my signature.

SAMUEL WHITE LINDSEY.
